UNITED STATES PATENT OFFICE

JOSEPH EDWARD FANNING, OF EAST ORANGE, NEW JERSEY

DESIGN FOR A WATCH CHAIN

Application filed August 1, 1931. Serial No. 40,750. Term of patent 3½ years.

To all whom it may concern:

Be it known that I, JOSEPH E. FANNING, a citizen of the United States, residing at East Orange, in the county of Essex, and State of New Jersey, have invented a new, original, and ornamental Design for Watch Chains, of which the following is a specification, reference being had to the accompanying drawings, forming part thereof.

Figure 1 represents a plan view of a watch chain showing my new design.

Figure 2 is a plan view of one of the link units.

Figure 3 is a side elevational view of the link unit shown in Figure 2.

Figures 4 and 5 show opposite end elevational views of the link unit of the design.

I claim:

The ornamental design for a watch chain as shown.

JOSEPH E. FANNING.
